Primary Examiner — Jasmine Mlinarcik*Assistant Examiner* — Victoria A. Rielly(74) *Attorney, Agent, or Firm* — Lucem, PC; Heedong Chae(57) **CLAIM**

The ornamental design for a compact container, as shown and described.

DESCRIPTION

FIG. 1 is a perspective view of the compact container showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the compact container shown in an open position.

The broken lines and unshaded areas adjacent to those broken lines define portions of the compact container that form no part of the claimed design.

1 Claim, 6 Drawing Sheets(56)
